FABRIC

Benjamin S. Faber, New York, N. Y.

Original application December 30, 1941, Serial No. 424,863. Divided and this application April 6, 1944, Serial No. 529,709

7 Claims. (Cl. 139—402)

This invention relates to a new and improved frieze pile fabric and has for an object to provide such a fabric in which the loops are woven in a warp-wise direction of warp pile yarn which is passed to and fro in a weft-wise direction over a warp-wise extending gauge or the like, while in the finished fabric, the loops lie and are held in a substantially warp-wise direction.

The invention consists in providing a fabric wherein the pile loops are formed without the use of any weft-wise extending threads, wires or the like for supporting the loops as they are formed.

Another object of the invention consists in providing a fabric wherein the threads are so arranged as to cause the loops to resist distortion or dislodgment with resultant lack of uniformity of the surface by reason of contact with objects exerting a pulling effect on one or more of the loops, or other vicissitudes of wear.

Another object consists in providing such a fabric wherein the loops may be formed of different heights on different parts of the fabric for the production of desired effects.

Another object consists in providing a fabric having a ground warp interwoven so as to extend longitudinally between the points at which alternate loops of each warp-wise row interweave or bind with the wefts, hereinafter referred to as the binding points of the loops, thus tending to prevent distortion or dislodgment of the loops by pulling strains thereon.

This application is a division of my application for Method of making fabric, Serial No. 424,863, filed December 30, 1941, now Patent No. 2,355,789, the method claims in which application were allowed on February 5, 1944. This application is for the product made in accordance with the method claims allowed in the parent application.

In weaving frieze pile fabrics, it has been customary to use gauges disposed warp-wise or longitudinally in the loom, which gauges support permanent or removable weft-wise threads, over which threads the warp pile yarn is passed to form loops of a height predetermined by the height of the gauges, the pile yarn, of course, being also interwoven with the ground of the fabric. In an alternative procedure, pile wires are inserted weft-wise and warp pile loops are formed thereover, the wires being drawn out after the formation of such loops.

In the fabric made according to my invention, the use of the said supporting weft threads or wires is entirely obviated, and the warp pile yarn is woven in such a relationship to the gauges

and the ground of the fabric that the resulting pile loops, though woven to and fro over gauges with a motion that includes weft-wise as well as warp-wise travel, are definitely positioned and held in the finished material in a warp-wise direction. Furthermore, the loops are so arranged with respect to certain of the ground threads that they strongly resist distortion or dislodgment such, for instance, as the "running" which is a characteristic defect of frieze materials under certain conditions of wear.

The fabric and two weaves thereof are represented in the accompanying drawing, in which

Fig. 1 represents a back plan view of a loose pile weave showing the fabric with the additional ground warp thread woven between the binding points of the row of pile loops,

Fig. 2 represents a side view of the fabric as illustrated in Fig. 1, and

Fig. 3 represents a detail back plan view of a portion of my new and improved fabric in a fast pile weave.

A fabric made in accordance with my invention comprises weft threads 5, pile warp threads 6 and an additional ground warp thread 7. This additional ground warp thread 7 which is interwoven with the weft threads 5, tends to hold the pile warp threads 6 and the weft threads 5 closely and firmly together so that distortion of the fabric or displacement of the threads is prevented. The regular ground warp threads 8 serve to space the pile and provide a firmly woven back in the usual manner. It will be noted that the pile warp 6 first binds on one side of the additional ground warp 7 and under weft thread 5 and then on the other side of 7. This alternation continues each time the pile 6 binds into the back of the fabric.

The relationship of the threads is well shown in the back plan view of Fig. 1 and it will be clear that, as a result of this warp-wise passage of the ground warp 7, and all its counterparts in the fabric, centrally between the binding points of the warp-wise rows of pile loops, a frictional binding effect is exerted on the loops where they interweave with the fabric ground so as greatly to increase the capacity of the loops to resist distortion, dislodgement or "running." While the primary function of the said extra ground warp 7 in the fabric is as just described, it also assists in maintaining the warp-wise positioning of the pile loops and, of course, adds strength to the fabric ground as a whole.

It should be stated that this invention is adaptable to many different loop pile weave constructions, and that the number and arrangement of

warp and weft threads illustrated and described is chiefly for the purpose of illustrating a practical and desired embodiment of my invention in a suitable weave construction. It has been chosen to show one form of loose pile loop weave as shown in Figs. 1 and 2, because, as previously indicated, an important feature of the invention resides in the fact that the arrangement and interlacing of the threads, particularly in the form of the invention shown in Figs. 1 and 2 of the drawing, tends to prevent the distortion or dislodgment of the loops by the pulling or drawing of them out of or away from the ground. The invention is not only applicable to other forms of loose pile weaves, with variations in warp and weft number, arrangement and interweaving, but it is also adaptable to different forms of fast pile weaves as shown in one form in Fig. 3 in which the pile yarn is so interlaced with the weft threads as to tend to prevent the pile loops from pulling out or away from the ground or losing height. In all these weaves an important novel feature of the invention resides in the definite, precise, and permanent warp-wise disposition of the pile loops and in their resistance to distortion or dislodgment.

It may additionally be noted that, by varying the size or count and number of threads, and by changing the height of the gauges or using gauges of differing heights, the width and height of all or some of the pile loops can be varied with corresponding modification in the surface effect. Likewise, the size, material composition, visual finish and twist of the yarns or threads may be changed or modified to suit the requirements in hand, as natural and artificial yarns, including both animal and vegetable fibers or filaments, may be employed to advantage under different circumstances.

It will be understood that various changes may be resorted to in the form, construction, arrangement and material of the various elements, without departing from the spirit and scope of my invention; hence I do not intend to be limited to the details herein shown and described except as they may be included in the claims.

What I claim is:

1. A pile fabric comprising, interwoven ground warp and weft threads, and warp pile threads each bound under alternate weft threads and over intermediate weft threads, said warp pile threads forming loops on the fabric surface lying in a warp-wise direction between ground warp threads, and an additional ground warp thread serving as a center line for its respective pile warp thread which pile thread binds on alternate sides of said additional ground warp thread and thus the pile loops are held effectively against distortion.

2. A pile fabric comprising, interwoven ground warp and weft threads, and warp pile threads each bound under alternate weft threads and over intermediate weft threads, said warp pile threads forming loops on the fabric surface lying in a warp-wise direction with a plurality of ground warp threads on each side thereof, and an additional ground warp thread serving as a center line for its respective pile warp thread which pile thread binds on alternate sides of said additional ground warp thread and thus the pile loops are held effectively against distortion.

said additional ground warp thread, and thus the pile loops are held effectively against distortion.

3. A pile fabric comprising, interwoven ground warp and weft threads, and warp pile threads each bound under alternate weft threads and over intermediate weft threads, said warp pile threads forming loops on the fabric surface lying in a warp-wise direction between ground warp threads, and an additional ground warp thread interwoven with weft threads and serving as a center line for its respective pile warp thread while pile thread binds on alternate sides of said additional ground warp thread and thus the pile loops are held effectively against distortion.

4. A pile fabric comprising, interwoven ground warp and weft threads, and warp pile threads each bound under alternate weft threads and over intermediate weft threads, said warp pile threads forming loops on the fabric surface lying in a warp-wise direction with a plurality of ground warp threads on each side thereof, and an additional ground warp thread interwoven with weft threads and serving as a center line for its respective pile warp thread which pile thread binds on alternate sides of said additional ground warp thread and thus the pile loops are held effectively against distortion.

5. A pile fabric comprising, interwoven ground warp and weft threads, and warp pile threads each bound under alternate weft threads and over intermediate weft threads, said warp pile threads forming loops on the fabric surface lying in a warp-wise direction between ground warp threads, and additional ground warp threads interwoven with weft threads and serving as a center line for their respective pile warp threads while pile threads bind on alternate sides of said additional ground warp threads, said additional ground warp threads being woven over the weft threads oppositely to the pile threads.

6. A pile fabric comprising, interwoven ground warp and weft threads, and warp pile threads each bound under alternate weft threads and over intermediate weft threads, said warp pile threads forming loops on the fabric surface lying in a warp-wise direction with a plurality of ground warp threads on each side thereof, and additional ground warp threads interwoven with weft threads and serving as a center line for their respective pile warp threads which pile threads bind on alternate sides of said additional ground warp threads, said additional warp threads being woven over the weft threads oppositely to the pile threads.

7. A pile fabric comprising interwoven ground warp and weft threads and warp pile threads each bound under and over weft threads, said warp pile threads forming loops on the fabric surface lying in a warp-wise direction between ground warp threads, and an additional ground warp thread interwoven with weft threads and serving as a center line for its respective pile warp thread which pile thread binds on alternate sides of said additional ground warp thread and thus the pile loops are held effectively against distortion.

BENJAMIN S. FABER.
